LIQUID DISPENSING APPARATUS.

Filed July 25, 1931

FIG. 1.

Patented Aug. 9, 1932

1,870,918

UNITED STATES PATENT OFFICE

JOSEPH A. LOGAN, OF SPRINGFIELD, MASSACHUSETTS, ASSIGNOR TO GILBERT & BARKER MANUFACTURING COMPANY, OF WEST SPRINGFIELD, MASSACHUSETTS, A CORPORATION OF MASSACHUSETTS

LIQUID DISPENSING APPARATUS

Application filed July 25, 1931. Serial No. 553,062.

This invention relates to improvements in liquid dispensing apparatus, such for example as is used for dispensing gasoline, oil and the like.

5 The invention is more particularly directed to that type of apparatus, known in the trade as a "meter pump" and including a meter interposed in a delivery conduit with some suitable means for forcing liquid there-
10 through. The delivery conduit usually terminates in a flexible hose, having at its discharge end a valved hose nozzle. Such nozzle usually has a self-closing valve, which is adapted to be manually opened by means of a
15 hand lever. The valve is moved to, and held in, closed position by a powerful spring.

This invention is directed to the provision of means for overcoming a certain trouble, which I have found has been the cause of
20 inaccurate measurement in apparatus of the general class above described. The trouble is due to the use of a flexible hose as a part of the delivery conduit. Without such hose, the trouble does not arise. The difficulty in
25 connection with the hose is that it can and does stretch to a considerable degree under certain conditions. It is extensible and contractible within appreciable limits and, in a sense, forms an elastic conduit connection be-
30 tween the fixed piping of the apparatus and the hose nozzle. With this condition in mind, it will be appreciated that if and when the fast moving stream of liquid flowing through the hose is suddenly arrested, as by
35 a sudden rather than a gradual closing of the hose nozzle valve, the momentum of the stream will exert a push on the closed valve and cause a stretch in the elastic hose. The action is essentially that of a liquid hammer.

40 An abnormally heavy pressure is momentarily built up, causing stretching of the hose and thereby increasing the volume of its liquid containing space. Then this abnormal pressure is gradually relieved and the hose contracts, thereby decreasing the volume of said space to normal and resulting in a backward surge of liquid. A certain part of the liquid, which has passed through the meter and been measured, is forced back through
50 the meter on the backward surge, when the

hose contracts, with the result that less liquid is delivered than is shown on the meter.

The invention has for its object the provision of means, located between the outlet of the meter and the inlet end of the hose, 55 to prevent the backward surge of liquid created in the hose, as above described, from passing back to or through the meter.

The invention will be disclosed with reference to the accompanying drawing, in 60 which:—

Fig. 1 is an elevational view, partly in section, of a meter pump embodying my invention;

Fig. 2 is a fragmentary sectional view of 65 the hose nozzle;

Fig. 3 is a fragmentary sectional view showing the connection between the hose and the fixed piping of the apparatus and showing also the preventative means of my invention; and 70

Fig. 4 is a fragmentary sectional view taken on the line 4—4 of Fig. 1.

Referring to this drawing, there is shown in Fig. 1, by way of illustrative example, one 75 form of "meter pump" in which my invention may be embodied. It includes a rotary pump 6, adapted for connection by piping shown in part at 7, with a low level liquid supply tank and arranged to force the liquid, 80 lifted from such tank, through a delivery conduit, which includes rigid pipe sections 8 and 9 and a flexible hose section 10. Interposed in the delivery conduit is a suitable meter, preferably and as herein indicated of the reciprocating piston type. The upstanding cylinder barrel is shown at 11 and, mounted on and above this barrel, is a register including a stationary graduated dial 12 and a movable indicator hand 13 adapted to be turned by the 85 reciprocating movement of the piston (not shown) within cylinder 11 by any of the suitable and well known means available for the purpose. Such means is arranged to turn hand 13 in the same direction on the upstroke 90 as on the downstroke of the piston. This characteristic, in some cases, has a bearing on the problem for which this invention offers a solution, as will appear. On the free end 95 of the hose 10, is a nozzle 14, having a valve 100

15 (Fig. 2), normally held closed by a spring 16 and adapted to be opened by a hand lever 17 (Fig. 1), which is pivoted to the nozzle body and engageable with the stem 18 of the valve. The pump is driven by an electric motor 19 which may be controlled in any suitable manner, as by a hand lever 20, adapted to operate a suitable switch, not shown.

The apparatus, above described, may be 10 housed in a casing 21, except for the hose and nozzle, the latter having a suitable support 22 on the exterior of the casing. The casing 21 encloses the space between base and cap members 23 and 24, respectively, and these members 15 are interconnected by a series of pipe columns 25, from which the motor, pump, and meter are suitably supported, as indicated in Fig. 1.

The hose 10 may be connected directly to 20 the end of pipe 9. Usually, however, it is desired to have a flow indicator interposed in the delivery conduit and, in such cases, the indicator is connected to pipe 9 and the hose 10 is connected to the indicator, as shown. 25 This flow indicator includes a glass cylinder 25', suitably clamped between, and closed at its ends by two end members 26 and 27. Within the cylinder there may be a spinner 28 adapted to be rotated by the liquid. The 30 pipe 9 and hose 10 are connected to the lower end member 27 in the manner clearly shown in Fig. 3. It will be seen that liquid forced by the pump through pipe 9 will enter the glass cylinder 25 by way of a passage 29 and 35 pass out of the cylinder, by way of a central passage 30, into hose 10. Within this passage 30 is a check valve 31, normally held closed by a spring 32 but adapted to open outwardly (in the normal direction of liquid flow) 40 under the pressure built up by pump 6.

It is common in meter dispensing systems of the general character described to provide a relief valve controlled by-pass around pump 6 to prevent the building up of dangerous pressures in the system, when the pump is 45 in operation while the nozzle valve is closed. In this particular case, such provisions happen to be built into the pump itself, as will appear from Fig. 4. The supply pipe 7 delivers liquid into a chamber 33 from which it 50 passes through the wall of a filter 34. Liquid leaves through the upper end of the filter, entering a chamber 35 and then passes into the inlet port 36 of the pump. The outlet 55 port of the pump is shown at 37, connected to pipe 8. A valve 38, normally held closed by a spring 39, blocks off communication between the outlet and inlet ports. When sufficient pressure is built up in the outlet, say for 60 example 20 pounds per square inch, valve 38 will open and liquid will be by-passed around the pump.

It is also common to provide in the hose nozzle an outwardly opening check valve 40 65 (Fig. 2) which is normally held closed by a

spring 41. This valve opens only after a predetermined pressure has been built up in the dispensing system. It prevents the delivery of liquid under lesser pressures, such for example as might be insufficient to cause accurate measurement of the liquid by the meter. It is often desirable for other reasons to have such a valve close to the delivery end of the hose to prevent any possibility of draining the hose. This check valve is not necessary to my invention and is shown merely because it forms part of the usual equipment. It may be omitted, if desired.

My invention is based upon the use of a check valve located in the delivery line somewhere between the outlet of the meter and the inlet of the hose, such for example as the check valve 31. This valve may be used to accomplish some of the work intended to be accomplished by the check valve 40, but it has another and more important purpose which is not and cannot be accomplished by the check valve 40 nor by a check valve at any other than the location described, i. e., between the outlet of the meter and the inlet of the hose. The valve, thus located, solves a particular problem in the art of meter pumps where, as here, such pumps are equipped with a flexible hose. The root of the trouble is that the hose is extensible to a certain extent and to such an extent as to cause inaccurate registration on the meter dial, under certain conditions of operation of the system.

The condition which causes the most serious trouble, is the one where the operator suddenly closes the hose nozzle valve 15, allowing the full force of the spring 16 to be released at once for action on the valve. The valve closes with a sudden snap and instantly arrests the column of liquid which had theretofore been moving at high velocity through the delivery conduit. The illustrated pump has a capacity of from 16 to 17 gallons per minute and normally delivers liquid from the nozzle, when its valve is fully open, at the rate of about 14 gallons per minute under about 10 to 12 pounds pressure. These figures are given to illustrate the point of high velocity and are not to be taken as limitations. It will be appreciated that, on the sudden stopping at the nozzle of a column of liquid moving at such velocity, a liquid hammer action is set up. A very high pressure is momentarily built up in the hose,—a pressure considerably in excess of any normal pressure in the system. The liquid, tending to continue in motion, acts on the closed nozzle valve with a push and this outward push acts on the elastic hose and stretches it. More than the normal volume of liquid will then be contained in the hose. Following this action, the high pressure, momentarily built up in the hose, is relieved by the liquid passing back through the meter. The hose contracts and,

in so doing, some liquid is expelled therefrom. Thus, a certain amount of liquid which has once passed through the meter and been measured, is subsequently passed back through 5 the meter with the result that the meter reading is inaccurate. It will show a quantity greater than that which has actually been delivered.

In certain kinds of piston meters, the liquid 10 can move back through the valves of the meter without moving the piston of the meter or at least without moving it much. In other types of piston meters, the valve arrangement is such that the backward surge, 15 set up as above described, would have to move the piston in a direction reverse to that in which it had been moving when the nozzle valve was suddenly closed. Backward movement of the piston would nevertheless cause 20 forward movement of the indicator hand. Then, there would result a double error in measurement. A certain quantity of liquid, equal in volume to the increase in volume of the hose caused by its stretching, would thus 25 be measured twice but not delivered to the customer.

The backward surge may be caused in other ways than by a sudden closing of the outlet 30 valve in the hose nozzle. A quick bending 35 of the hose, while the nozzle valve is closed, will tend to create a backward surge and cause a similar trouble although usually not to such a great degree.

It is perhaps also possible that some elongation of the hose may in some cases be caused 35 due to the difference in pressures existing therein when the nozzle valve is opened and closed. With the nozzle valve closed and the 40 pump in operation, a higher pressure exists than when the nozzle valve is open. That is, the by-pass valve is usually set to open at a pressure higher than the normal pressure needed to force liquid through the delivery conduit. If the difference in pressure is sufficient, some stretching of the hose may result 45 in the interval between the closing of the nozzle valve and the opening of the by-pass valve. Then, when the by-pass valve opens, the pressure will be relieved and the hose will 50 contract with the result that a backward surge may be set up. This condition is not a bothersome one with the particular pump herein described, but it may possibly result in some trouble in other kinds of pumps.

55 The check valve effectively prevents the backward surge of liquid, caused by any of the conditions above described or otherwise, from forcing liquid back through the meter and from reversely operating the meter with 60 resulting inaccuracies of measurement.

The invention has been disclosed herein, in an embodiment at present preferred, for illustrative purposes, but the scope of the invention is defined by the appended claims 65 rather than by the foregoing description.

What I claim is:

1. In combination, a liquid delivery conduit, a meter interposed therein, a valved nozzle on the delivery end of said conduit, said conduit including a flexible and somewhat elastic section between said nozzle and meter, which section is extensible and contractible within limits, means for forcing liquid through said conduit, and an outwardly-opening, non-return valve located in said conduit between said flexible section and said meter. 70

2. In combination, a liquid delivery conduit, a meter interposed therein, a nozzle on the discharge end of said conduit, a valve in said nozzle, a hand lever for manually opening said valve, means for automatically and rapidly closing said valve when the hand lever is released, said conduit including a flexible and somewhat elastic section between said nozzle and meter, which section is extensible and contractible within limits, means for forcing liquid through said conduit, and an outwardly-opening, non-return valve located in said conduit between said flexible section 80 85 and said meter. 90

In testimony whereof I have affixed my signature.

JOSEPH A. LOGAN.
